UNITED STATES PATENT OFFICE.

WILLIAM H. WHITE, OF BURRILLVILLE, RHODE ISLAND.

SHUTTLE-MOTION FOR LOOMS.

SPECIFICATION forming part of Letters Patent No. 743,123, dated November 3, 1903.

Application filed February 7, 1900. Serial No. 4,394. (No model.)

To all whom it may concern:

Be it known that I, WILLIAM H. WHITE, a citizen of the United States, residing at Burrillville, in the county of Providence and State of Rhode Island, have invented certain new and useful Improvements in Shuttle-Motions for Looms, of which the following is a specification, reference being had therein to the accompanying drawings.

Like numerals indicate like parts.

Figure 1 is a front elevation showing one end of a loom-lathe, two shuttle-boxes thereon, a picker-stick with means to operate the same, the sword, and lathe, the latter having the shuttle-races, upper race and lower race, hand-rail, and two sets of reeds, these features being of old form. Fig. 2 is a view of my invention, showing in front elevation one end of the loom-lathe, two shuttle-boxes, a picker-stick and cross-head thereon, two pickers carried by said cross-head, and also the adjacent parts of the device. Fig. 3 is a rear elevation of said cross-head. Fig. 4 is a front elevation thereof. Fig. 5 is a side elevation thereof. Fig. 6 is a detail view.

My invention relates to looms for weaving cloth; and it consists in the novel construction and combination of the several elements hereinafter particularly described, and set forth in the claims.

In the drawings, 1 is the lathe-sword, 2 the lathe, and 3 the hand-rail. The sword is pivotally mounted at 4 to the frame 5. The picker-stick stand 6 extends from the frame 5, and on said stand 6 the picker-stick 7 is pivotally mounted at 8. A strap 9, fastened to the picker-stick 7 near the bottom thereof by the screw 10, passes over the rounded lower end of the picker-stick, and a spiral spring 11 is hooked at one end to said strap and at the other end to an eye 12 of a plate 13, bolted to the floor.

The sweep-arm of the loom is shown at 14, and at its upper end it is pivotally connected 45 to the sweep-stick 15, which has at its outer end the lug-strap 16, surrounding the picker-stick 7 and kept in position by the strap 17, the latter being secured at 18 to the picker-stick 7.

50 There are two shuttle-boxes 19 and 20 and an upper race-plate 21. A set of reeds 22 extends from the lathe 2 to the race-plate 21,

and a set of reeds 23 extends from the race-plate 21 to the hand-rail 3.

The picker 24, Fig. 1, is movable on the race-rod 25 and is connected by the picker-strap 26 to the picker-stick 7. The race-rod 25 is supported in the bearings 27 28. The shuttle 29 is shown in the shuttle-box in Fig. 6.

In order to weave two strips of cloth at the same time upon the loom, I use two shuttles 29 of ordinary construction, one moving on the shuttle-race of the lathe 2, as heretofore, and the other on the upper race-plate 21. The upper shuttle is driven from one shuttle-box 20 on one end of the loom-lathe to another shuttle-box on the opposite end of the loom-lathe by means of pickers 30, and the lower shuttle is driven from one shuttle-box 19 on one end of the loom-lathe to another shuttle-box on the opposite end of the loom-lathe by means of the pickers 24. The picker 30 is mounted on the race-rod 31, which is supported by the bearings 32 33. The picker 30 is secured to the upper end of the picker-stick 7 by the picker-strap 34.

The construction shown in Fig. 1 is old, but the construction shown in Figs. 2 to 6, inclusive, embodies my invention herein described and claimed.

A cross-head 35 receives motion from each picker-stick 7. The construction of the cross-head is shown in detail in Figs. 3, 4, and 5, where it is seen that it consists of a plate substantially rectangular in outline, near the center of which a block 36, somewhat elliptical in peripheral outline, is fastened by means of a bolt 37. On the back of the plate of the cross-head are secured by screws 38 two bearings 39 40 at the top and two others 41 42 at the bottom, by which the cross-head 35 is mounted and slideable on the race-rods 25 31. The bearing 39 is semitubular, and the bearing 40 is a plate with a half-round longitudinal groove. In like manner the bearing 42 is semitubular, and the bearing 41 is a plate with a half-round longitudinal groove. These bearings have oilers 43 44 thereon to lubricate them, as seen in Figs. 3 and 5. The cross-head 35 has on one side at the top and bottom an angularly-projecting lip 45. A strap or loop 46 is fastened by screws 47 to the picker-stick 7, and the block 36 of the cross-head 35 is between the strap 46 and the picker-

stick 7. Picker-straps 34' connect the cross-head 35 with the picker 30', being fastened at the ends thereof by the screws 48 49, and picker-straps 26' connect the cross-head 35 with the picker 24', being fastened at the ends thereof by the screws 50 51.

Having thus enumerated and described the said parts of my improved loom, I will now explain the operation thereof. The warps 10 for the lower strip of cloth pass from the yarn-beam over the whip-roll, through the eyes of the heddles of the harness-frame, thence through the reeds 22, over the top or raceway of the lathe 2, where by the shuttle 15 driven on said raceway alternately from side to side from one shuttle-box 19 to the other by the force of the picker and picker-stick a filling-thread is woven in the warps in the shed thereof made by the rise and fall of the 20 harnesses, as usual. The cloth so woven passes over the breast-beam through the aperture therein and is wound on the cloth-roll. At the same time the warps for the upper strip of cloth pass from an upper yarn-beam 25 over an upper whip-roll, through upper eyes of the heddles of the harness-frame, thence through the reeds 22, over the top of the upper race-plate 21, carried by the swords 1, whereby the shuttle driven on said upper 30 race-plate 21 alternately from side to side from one shuttle-box 20 to another by the force of the picker and picker-stick a filling-thread is woven in the upper warps in the shed thereof made by the rise and fall of the 35 harnesses. The upper strip of cloth so woven passes over an upper beam and past the front surface of the lower breast-beam and is wound on the cloth-roll.

In the construction shown in Fig. 1 the 40 pickers 24 and 30 move with different velocities, because they are located at different radial distances from the pivotal point 8 of the picker-stick. Therefore in order to secure a uniform velocity for the upper and lower 45 pickers I prefer to use the cross-head 35, traveling on the race-rods 25 31 and carrying the two pickers 24' 30', movable on the same race-rods, respectively, as shown in Fig. 2. In this construction the picker-stick 7 delivers the 50 blow upon the one block 36, which, being connected by the bolt 37 to the cross-head 35, causes the latter to move on the race-rods 25 31, thus driving the two pickers 24' 30' on said rods, respectively, at the same time and with the 55 same velocity and power, and consequently the two shuttles also. As the picker-stick 7 moves back the strap or loop 46, attached thereto and which passes over the block 36, brings back by means of said strap the cross-head 35 to its former position, because said block 36 is bolted to the cross-head 35, as shown. The angularly-projecting lips 45 of the cross-head 35 extend therefrom suffi-

ciently to deliver the blows upon the two pickers 24' 30' near the central axial line thereof. 65 I am thus able to weave two strips of cloth on one loom at the same time, and consequently diminish the cost and labor of the production of any stated quantity.

I claim as a novel and useful invention and 70 desire to secure by Letters Patent—

1. In combination with the picker-stick of a loom, two shuttle-boxes one above the other in which said picker-stick is capable of an oscillating movement, a cross-head having two bearing-plates on its rear surface, which are each provided with a half-round longitudinal groove, a semitubular bearing for each of the bearing-plates first aforesaid, provided with longitudinal flanges, fastenings for said bearing-plates and semitubular bearings connecting them with the cross-head, two race-rods for said shuttle-boxes, on each of which rods one of said bearing-plates and its companion semitubular bearing is mounted, a 80 picker mounted movably on each race-rod, a central picker-strap connecting each picker with the cross-head, a central block on said cross-head, two angularly-projecting lips from the rear surface of said cross-head located 85 and arranged to strike against said pickers, respectively, and a strap passing over said block and fastened at both ends to the picker-stick, substantially as shown.

2. In combination with the picker-stick of 95 a loom, two shuttle-boxes, one above the other, in which said picker-stick is capable of an oscillating movement, a picker, a cross-head having two bearing-plates on its rear surface, which are each provided with a half-round 100 longitudinal groove, a semitubular bearing for each of the bearing-plates first aforesaid, fastenings for said bearing-plates and semitubular bearings connecting them with the cross-head, an oiler for each of said semitubular bearings having a duct leading through 105 it to the interior surface thereof, two race-rods for said shuttle-boxes, on each of which rods one of said bearing-plates and its companion semitubular bearing is mounted, a picker 110 mounted movably on each race-rod, a picker-strap connecting each picker with the cross-head, a central block on said cross-head, two angularly-projecting lips from the rear surface of said cross-head located and arranged 115 to strike against said pickers, respectively, and a strap passing over said block and fastened at both ends to the picker-stick, substantially as set forth.

In testimony whereof I affix my signature 120 in presence of two witnesses.

WILLIAM H. WHITE.
